UNITED STATES PATENT OFFICE.

GEORGE W. ARPER, OF OAKLAND, CALIFORNIA.

STEAM-GENERATOR FOR HYDROCARBON-BURNERS.

SPECIFICATION forming part of Letters Patent No. 758,807, dated May 3, 1904.

Application filed December 9, 1902. Serial No. 134,481. (No model.)

To all whom it may concern:

Be it known that I, GEORGE W. ARPER, a citizen of the United States, residing at Oakland, county of Alameda, State of California, have invented certain new and useful Improvements in Steam-Generators for Hydrocarbon-Burners; and I do hereby declare the following to be a full, clear, and exact description of the same.

10 The present invention relates to an improved construction of steam-generators for hydrocarbon-burners whereby the supply of water into the generating-cylinder is automatically controlled by the pressure of the generated steam, the connection of the outlet-pipe for the generated steam with the steam-generating cylinder being such as to provide against sediment within the cylinder entering therein and clogging the discharge-nozzle.

15 20 To comprehend the invention, reference should be had to the accompanying sheet of drawings, wherein—

Figure 1 is a perspective view illustrating the generator and the hydrocarbon-burner applied to an ordinary cooking stove or range, and Fig. 2 is a longitudinal sectional view of the generator and burner removed from the stove or range.

The numeral 1 is used to indicate an ordinary cooking range or stove, and 2 the heating-chamber thereof. Within the said chamber is arranged the fire-pot 3, into which oil is delivered from the supply-pipe 4. The fire-pot 3 is formed with an oil-seat 5, into which the oil delivered from end 6 of the supply-pipe 4 is received. Above the discharge end 6 of the supply-pipe is arranged a deflecting disk or plate 7, which is supported a slight distance above the discharge end 6 by the 30 35 40 downward extensions 8. The supply of oil or hydrocarbon through the supply-pipe 4 is regulated by the controlling-valve 9.

Through the wall 10 of the range or stove 1 extends the steam-generating cylinder 11, which projects into the heating-chamber 2 above the fire-pot 3. The outer end of the cylinder 11 is provided with a plug 12, which screws therein. The removal of this plug permits of the insertion of a tool into the cylinder for the purpose of cleaning same.

To the cylinder 11 outside of the stove or range connects the water-supply pipe 13, the supply of water therethrough into the cylinder being regulated by the controlling-valve 14.

From the inner end portion of the steam-cylinder at its top extends the outlet-pipe 15 for the generated steam. This pipe extends through the wall 16 of the stove or range and then returns to the heating-chamber, a controlling-valve 17 being interposed within the 55 outside section of the pipe. To the free end of said pipe is attached a discharge-nozzle 18, which is arranged to deliver a jet of steam onto the deflecting or spreader plate or disk 7.

To prevent heavy sediment of the water 65 delivered into the steam-generating cylinder, which sediment moves over the wall of the cylinder, being carried into the steam-outlet pipe and clogging the jet-nozzle thereof, the receiving end 19 of said pipe extends into the 70 cylinder 11 a short distance below the upper surface thereof.

In case the water fed into the cylinder 11 fills the same prior to generation of steam, and thereby causes water to be delivered into 75 the fire-pot through the discharge-nozzle 18, it is only required that the controlling-valve 17 be closed. When thus closed, the pressure of the steam as generated will overcome that of the water-pressure and gradually force the 80 water back into the supply-pipe. After the generation of steam within the cylinder 11, the pressure thereof will regulate the feed of water into the cylinder in proportion to the consumption thereof by being discharged into 85 the fire-pot. The supply of water into the steam-cylinder may thus be said to be automatically controlled by the pressure of the generated steam.

By the foregoing-constructed steam-generator the arrangement of the outlet-pipe for the steam is such as to prevent the water-sediment being delivered to the discharge-nozzle, while at the same time an excess of water feed into the cylinder 11 is obviated by reason of the 95 counter-pressure of the generated steam.

The steam as ejected from the discharge-nozzle strikes against the disk or plate 7 and is broken up and deflected into the flame of burning hydrocarbon within the fire-pot, the 100

heat from which bears against the steam-generating cylinder 11.

Having thus described the invention, what is claimed as new, and desired to be protected 5 by Letters Patent, is—

In a stove having a heating-chamber, the combination with a hydrocarbon-burner therein, of a steam-generator located above said burner, comprising a cylinder, the outer end 10 of which extending without the heating-chamber and having a removable closure, a water-supply pipe communicating with said cylinder at said extended portion, and an outlet-pipe for the generated steam, comprising op-

positely-disposed members, the communicating ends of which extending without the heating-chamber, a regulating-valve in said extended portion, one of said oppositely-disposed members passing through the top of the cylinder to a point beyond the inner surface thereof, and the other member terminating in a nozzle. 15 20

In witness whereof I have hereunto set my hand.

GEORGE W. ARPER.
